PORTABLE KILN

Carl S. Bang, Montreal, Quebec, Canada

Application April 19, 1937, Serial No. 137,789
In Canada April 25, 1936

6 Claims. (Cl. 202—213)

This invention relates to kilns and more particularly for those employed in the carbonization of wood and the production of charcoal.

The object of my invention is to provide a kiln 5 in which the escaping heated gases pass through the hollow walls and form an insulating jacket to the chamber in which the treatment is being carried on.

A further object is to provide a kiln of a portable weight mounted on trunnions on a stand whereby it can be readily tilted to a horizontal position to facilitate the filling and emptying operations.

A further object is to provide a means to charge 15 the kiln with wood in an improved manner whereby a higher grade of charcoal is produced.

Other objects will be set forth hereafter.

Reference is made to the accompanying drawing in which:

20 Figure 1 is a side view of the kiln partly in section.

Figure 2 shows the kiln mounted on its stand and the means of tilting it.

Figure 3 is a cross section of Figure 1 on the 25 line 3—3 looking downwards.

Figure 4 is a plan view.

As shown in Figure 1 the kiln is in the form of a cylinder 1, having slightly conical top 10 and bottom 11. An inner wall 12, and lower top 13 30 provide a connected passage to a central outlet 14. The top 13 has also a central opening 15.

Towards the lower part of the wall 1 a plate 16 35 cuts the passage between the walls 1 and 12 into an upper passage 17 and a lower passage 18. A continuous opening 19 above the plate 16 provides an entrance from the interior of the kiln 2 to the passage 17. An opening 21 at the bottom of the inner wall 12 provides an inlet from the passage 18 into the interior 2. A series of valved 40 inlets 22 to the passage 18 provide the control of the air supply to the kiln. The bottom 11 is provided with two or more manholes 23 with covers 24. In the center of the bottom 11, there is 45 an outlet 25 into a pipe 26 to provide for the removal of the fluid products of the treatment. Half way up the inner wall 12 is a ring or plate 27 secured by vertical supports to that wall to permit the free flow of gas down the wall to the outlet 19. The outlet 25 has a cover or grating 28 with open sides 29 to protect it from being blocked by solid matter from above.

The cylinder 1 is provided with a pair of trunnions 3 firmly secured to the outer and inner walls. On the outer edge of the top 10 at points

at right angles to the trunnions 3 are secured rings 30 to connect with the tilting apparatus.

The outlet 14 has an adjustable cover 31 to control the escaping gases and smoke. The outlet 15 has a cover 32 adapted to a sand seal. 5

The stand 4 has suitable bearings 40 for the trunnions 3 at a height sufficient to permit the kiln to rotate freely. The side members 41 of the stand 4 are connected at one end of their bases by a bar 42 on which are mounted, at the 10 middle a block 43 and at one end a block 44. The side member 41 extends upwards a distance above the top of the kiln when mounted on its trunnions 3 and at its upper end has a bracket to which a block 46 is hooked. A rope 5 with a hook 15 50 is attached to the ring 30 and passes through the blocks 43, 44 and 46 and is connected to a perforation 45 at the lower end of the side member 41 by a block and tackle 47 or similar mechanism. 20

Beneath the outlet pipe 26 is placed a deep pan 6 to receive the liquid outflow from the kiln and to provide a water seal to the pipe 26.

With a construction similar to that above described, the operation of the device is as follows: 25

In order to charge the kiln with the logs of wood to be treated, by means of the block and tackle the kiln is rotated into a horizontal position and the manhole covers are removed. The wood in logs about half the length of the kiln, 30 are then placed in the interior in the position as shown in Figure 1. Owing to the ring or plate 27 the upper tier of the logs will incline outwardly, while the lower tier will incline inwardly. This arrangement provides an unobstructed passage 35 for the smoke and gases down the inner wall 12 to the opening 19 to the wall passages 17 and thence to the outlet 14.

When the kiln has been fully charged with logs, the covers over the manholes are replaced 40 and secured, and the kiln is tilted back to a vertical position.

The charge of wood is then ignited through the top openings. The lower top opening has its cover adjusted and is preferably sealed by a sand 45 seal. This sand seal acts as a safety valve to the interior of the kiln, should the pressure of the gases become too high.

The air inlets are then adjusted to supply the required amount of air. The top cover is then 50 adjusted to provide a sufficient draught through the kiln. Readjustment of the air valves and the top cover will be made during the operation of the treatment.

The pan is placed under the bottom outlet 55

pipe, and filled with sufficient water to provide a water seal to the pipe.

Owing to the interior of the kiln being surrounded by a heated area, the walls are prevented from cooling, however low the external temperature may be. The effect of this protection is that the process of carbonization of the charge of wood takes place more uniformly than has hitherto been possible.

10 Furthermore, by arranging the charge of logs in the kiln in the manner shown in Figure 1, the circulation and removal of the gases is maintained throughout the operation and a uniform treatment is obtained. As both tiers of the 15 charge will descend toward the center of the kiln as shrinkage takes place, there is less liability of the product being broken up.

By these means, a higher quality of charcoal is produced and also a higher percentage of the 20 charge is converted into charcoal and is not consumed in the process.

The outlet pipe at the bottom of the kiln provides for the rapid removal of the liquid products of the treatment. The cover or grating prevents the solid charge from blocking this outlet, while the water seal prevents the escape of gas through the outlet pipe.

When the process of carbonization has been completed, the air inlets are closed, and the cover 30 of the gas outlet is secured in a closed position. The kiln is then allowed to cool off before the removal of the charcoal.

After cooling the kiln is again tilted to a horizontal position, the manhole covers removed and 35 the product of the treatment is withdrawn.

It is obvious that the shape of the kiln is not limited to a cylindrical form, but may be made in other suitable forms with similar functions.

What I claim is:

40 1. In a portable kiln, a shell supported by trunnions on a stand, having double walls, forming an annular vertical flue, end plates to the walls providing a passage from the top of the flue to a central outlet, a horizontal dividing plate between the walls below an opening from the interior of the kiln in its lower portion, air inlets to the flue below the plate, with an outlet from this portion of the flue to the interior of the kiln at its bottom, openings in the bottom of the 45 kiln for inserting the charge, and a central outlet in the bottom and means to tilt the kiln to a horizontal position.

55 2. In a portable kiln, a shell supported by trunnions on a stand, having double walls forming an annular vertical flue, end plates to each wall forming a passage from the top of the flue to a central controlled outlet in the upper end plate, a horizontal dividing plate at the lower portion of the walls forming upper and lower 60 flues, an outlet from the interior of the kiln to the upper flue above the plate, air inlets to the flue below the plate and outlets from this portion of the flue to the bottom space of the kiln, man holes in the bottom of the kiln for charging and 65 emptying the kiln, a central outlet in the bot-

tom having a water seal and a central outlet in the top of the kiln having a cover thereto and means to tilt the shell to a horizontal position.

3. In a portable kiln, a shell supported by trunnions on a stand, having double walls forming an annular vertical flue, end plates to each wall forming a passage from the top of the flue to a central controlled outlet in the upper end plate, a horizontal dividing plate at the lower portion of the walls forming upper and lower flues, an outlet from the interior of the kiln to the upper flue above the plate, air inlets to the flue below the plate and outlets from this portion of the flue to the bottom space of the kiln, man holes in the bottom of the kiln for charging and emptying the 10 kiln, a central outlet in the bottom having a water seal and a central outlet in the top of the kiln having a cover thereto, a narrow plate with vertical supports a short distance within the 15 middle of the inner wall, and means to tilt the shell to a horizontal position.

4. In a portable kiln, a shell supported by trunnions on a stand having double walls forming an annular vertical flue, end plates to the outer walls forming top and bottom to the kiln, an upper end plate to the inner wall, central outlets to the top end plates the lower portion of the flue being cut off by a horizontal plate below an opening in the inner wall to the interior of the kiln, a series of controlled air inlets in the outer wall to the flue below the horizontal plate, which flue opens to the interior of the kiln at its bottom, 20 openings in the bottom of the kiln and means to tilt the kiln to a horizontal position.

30 5. In a portable kiln, an outer shell supported by trunnions on a stand having slightly conical top and bottom, a central outlet to the top, openings in the bottom to insert the charge, an inner shell having a top forming an annular flue leading to the central outlet, an opening in the inner shell in its lower portion a horizontal plate in the flue below the opening cutting off the section below the plate, which section opens at its bottom to the interior of the kiln, a series of 40 controlled air inlets to this section of the flue and 45 means to tilt the kiln to a horizontal position for filling and emptying the charge.

35 6. In a portable kiln, an outer shell supported by trunnions on a stand having slightly conical top and bottom, a central outlet to the top, openings in the bottom to insert the charge, an inner shell having a top forming an annular flue leading to the central outlet, an opening in the inner shell in its lower portion, a horizontal plate in the flue below the opening cutting off the section below the plate, which section opens at its 50 bottom to the interior of the kiln, a series of controlled air inlets to this section of the flue, an outlet in the top of the inner shell below the central outlet and an outlet in the center of the 55 bottom of the kiln, and means to tilt the kiln to a horizontal position for filling and emptying the charge.
